UNITED STATES PATENT OFFICE.

ADAM PYLE, OF MUSKEGON, MICHIGAN, ASSIGNOR TO SUPERIOR MANUFACTURING COMPANY, OF MUSKEGON, MICHIGAN, A CORPORATION OF ILLINOIS.

DESIGN FOR A SIDE STANDARD OF OPERA-CHAIRS.

No. 39,891.

Specification for Design.

Patented March 23, 1909.

Application filed January 11, 1909. Serial No. 471,811. Term of patent 14 years.

To all whom it may concern:

Be it known that I, ADAM PYLE, a citizen of the United States, residing at Muskegon, in the county of Muskegon and State of Michigan, have invented a new, original, and ornamental Design for Side Standards of Opera-Chairs, of which the following is a specification, reference being had to the accompanying drawing, forming a part thereof.

Figure 1 is a side elevation of a side stand-

ard for opera chairs showing my new design. Fig. 2 is an edge elevation of the standard.

I claim:

The ornamental design for the side standard of an opera chair, as shown.

ADAM PYLE.
